US00D845972S

(12) **United States Design Patent** (10) Patent No.: **US D845,972 S**
Pranger et al. (45) Date of Patent: **** Apr. 16, 2019**

(54) **DISPLAY SCREEN WITH GRAPHICAL USER INTERFACE**

(71) Applicant: **ALEXANDER MACKENZIE & PRANGER**, Sandy, UT (US)

(72) Inventors: **Eugene Patrick Pranger**, Alpine, UT (US); **Timothy Eugene Pranger**, Eagle Mountain, UT (US); **Robert Eric Roy**, Riverton, UT (US)

(73) Assignee: **POPIO IP HOLDINGS, LLC**, Sandy, UT (US)

(**) Term: **15 Years**

(21) Appl. No.: **29/561,280**

(22) Filed: **Apr. 14, 2016**

(51) LOC (11) Cl. **14-04**

(52) U.S. Cl.

USPC **D14/486**

(58) **Field of Classification Search**

(57) **CLAIM**

The ornamental design for display screen with graphical user interface, as shown and described.

DESCRIPTION

FIG. 1 is a front view of a display screen with graphical user interface showing our new design; and,

FIG. 2 is a front view of a display screen with graphical user interface showing our new design.

The broken lines depict the display screen and form no part of the claimed design. The broken lines depict portions of the graphical user interface and form no part of the claimed design.

1 Claim, 2 Drawing Sheets
